Application January 11, 1939, Serial No. 250,315
In Germany January 6, 1938

9 Claims. (Cl. 179—171)

This invention relates to automatic electronic regulator circuits and more particularly relates to novel circuits for insuring undistorted audio frequency signal reproduction with such control circuits.

An important feature of the invention resides in materially simplifying prior circuit arrangements for automatic range control for neutralizing or compensating impulse shocks due to regulation voltages as to their effect upon the output circuit of the system. High quality volume control was previously obtained with push-pull electronic control stages comprising two opposed regulator or control tubes to avoid direct current shocks or impulses from appearing in the output circuit. In accordance with the present invention, extraneous impulse neutralization is obtained with a single tube. The principle depends upon the use of a separate grid electrode in a multi-electrode tube for the return or compensation path of the tube output circuit.

A further important feature of the invention resides in novel and useful methods of and circuits for obtaining regulation potentials for automatic dynamic expansion or range control for an audio frequency system. The regulation potentials are selectively obtained from the audio frequency signals employing different groups of signal frequencies within the audio frequency signal spectrum. Thus, in the preferred embodiment, by eliminating or filtering out the audio frequency band from thirty to one hundred and fifty or two hundred cycles per second from the control system, the prior art was able to avoid low frequency distortion, but impaired the dynamic regulation control. The present invention employs the low frequency band for a distinct but simultaneously applied regulator potential in conjunction with a control potential obtained from the higher frequencies. A filter having a relatively high time constant is applied for rectifying the low frequency band before application to the control tube. Undistorted dynamic control is effected in this way as will be more particularly set forth hereinafter.

Accordingly, it is an object of the present invention to provide novel and simplified circuit arrangements for a dynamic or volume control system which neutralizes direct current shocks or impulses from the regulation potentials in their effect upon the output circuit of the system.

Another object of the present invention is to provide novel control circuit arrangements for obtaining undistorted dynamic control in an audio frequency system.

A further object of the present invention is to provide a volume control system utilizing a balanced output from a single multi-electrode tube employing a grid electrode for the compensation circuit.

Still a further object of the present invention is to provide a dynamic range control system employing a plurality of frequency band groups from the audio frequency spectrum, and applying different time constants in the rectification thereof to obtain undistorted reproduction.

These and further objects of the present invention will become apparent in the following description taken in connection with the drawings, in which:

Figure 1 is a circuit diagram of a preferred volume control stage for neutralizing impulses and direct current shock to prevent their reaching the output circuit.

Figures 2 to 5 are modified arrangements for the automatic volume control stage of Figure 1.

Figure 6 is a circuit diagram of a system for sound record reproduction providing the shock neutralization principle in the amplification stage thereof in conjunction with dynamic control.

Figure 7 is a circuit diagram of the invention applied to sound reproduction embodying the undistorted dynamic expansion features of the invention.

Figure 8 shows an automatic tone control system embodying a multi-grid electron tube, and

Figure 9 shows an amplifier circuit embodying both automatic dynamic range and tone control in accordance with the invention.

In Figure 1 is illustrated a volume control stage employing a multi-electrode tube 10. The unidirectional or rectified regulation potential is applied to grid 11 in a conventional manner. Grid 11 is located adjacent indirectly heated cathode 12. The control signal is applied to control grid 13 shown adjacent anode 14. The invention is applicable to radio frequency as well as audio frequency as will be understood. The positive or screen grid 15 is connected to a suitable source of current supply through terminal 16. By-pass condenser 17 shunts the grid 15 to the cathode 12.

The output circuit comprising transformer 18 and series condenser 20 is connected between anode 14 of the tube and a return grid electrode 21 located between screen electrode 15 and regulator electrode 11. A voltage divider or potentiometer 22 is connected between anode 14 and grid 21, being in effect in parallel across the output circuit. The anode potential is applied from positive terminal 23 connected to a suitable source

to the variable tap connection of the voltage divider 22. Both anode 14 and grid 21 are thus placed at a positive potential with respect to the negative cathode 12.

The operation of the circuit of Figure 1 for neutralizing direct current shock excitations depends on the following factors:

The current flowing from positive grid 21 which is in the electrode stream of the tube is substantially unaffected by the signal voltage which is applied to control grid 13. This is due to the shielding effect of positive screen grid 15 interposed between return grid 21 and control grid 13, as shown. In operation, the current through return or compensation grid 21 depends only on the instantaneous value of the regulation or control potential applied to grid 11 interposed between it and the cathode. The current flowing through the plate or anode 14 follows the varying signal potential of the alternating current signals applied to the control grid 13. However, regulation electrode 11 controls the average density of the electron stream between cathode 12 and anode 14. Accordingly, the current flowing through anode 14 is a function both of the regulation and signal potentials.

Thus, the signals flowing to the primary of transformer 18 comprise amplified signal frequencies flowing into anode 14. The amplified signal frequencies pass through by-pass condenser 20 and coupling transformer 18. Variations in the regulation potential applied to grid 11 correspondingly affect the current flow both through anode 14 and positive grid 21. The current flow from these elements is in the same direction towards the primary of transformer 18 and are naturally subtractive in their voltage effect thereon. In accordance with the invention, the adjustment of the tap on voltage divider 22 is such as to control the respective potentials applied to anode 14 and grid 21 so as to balance or neutralize the current flow effects upon electrodes 14 and 21 due to the regulation by grid 11. This procedure causes equal signal effects upon transformer 18 by electrodes 14 and 21 due to the effects of grid 11 which cancels out when voltage divider 21 is properly adjusted, as will now be evident.

The signal frequencies applied to grid 13 are amplified and pass through transformer 18 for further application in a conventional manner. Direct current potential shocks or impulses originating at regulation grid 11 are accordingly neutralized and not applied to the transformer 18. The normal function of regulation of the automatic volume control for this stage is effective in the normal manner for controlling the amplification levels of the applied signals to grid 13. It is to be understood that voltage divider 22 shown as variable may, in a practical set, be a fixed voltage divider comprised of a tapped resistor, or two resistors of suitable value connected in series.

A modified form of the invention is illustrated in Figure 2 where positive screen grid 15 and compensation grid 21 of Figure 1 are interchanged, the return grid 21 being adjacent the control grid 13 and screen grid 15 adjacent regulation grid 11. In this form, the current through positive return grid 21 is influenced by the signal potentials applied to the control grid 13 located between grid 21 and anode 14. Direct current shocks in this case will neutralize to the desired degree after voltage divider 22 is suitably selected in the manner as already described in connection

with Figure 1. The arrangement of anode 14 and return grid 21 on opposite sides of control grid 13 acts as a push-pull scheme, which in the prior art required two individual electron streams.

In place of the voltage divider 22 it is feasible to arrange for shock impulse compensation by connecting the positive source terminal 23 to a midway tap in the primary winding 24 of transformer 18. In this case, the voltage divider 22 and condenser 20 is dispensed with and accurate balancing out of the shock potentials may be insured by connecting variable parallel resistances across each section of the tapped winding of the transformer, or by suitable resistances individually connected in series with the anode 14 and grid 21.

It is to be understood that as far as the basic idea of the invention is concerned, it is immaterial whether additional grids or electrodes are provided within the amplifier tube 10. Furthermore, it is not essential for the signals to include the anode 14 of the tube. In Figure 3 I have shown another form of the invention where anode 14 is connected directly to a suitable positive potential 25, and the positive grid electrodes 15 and 21 are connected across voltage divider 22 and the transformer 18. An impedance may be connected between anode 14 and positive terminal 25 if desired. The alternating current signals applied to grid 13 are variably amplified in accordance with the variation in potential applied to grid 11 and are passed through grids 15 and 21 with proper neutralization of the shock impulse excitations in a manner forming the basis of the present invention.

Figure 4 is a further form of the invention employing only three intermediate grid electrodes. Control grid 13 is dispensed with, and the control signal is applied between anode 14 and cathode 12. The regulation voltage is applied to grid 11 as in the previous examples. The output circuit is taken between positive grid electrodes 15 and 21, and applied across voltage divider 22 and transformer 18.

A further form of the invention is shown in Figure 5 where compensation grid 21 is interposed between regulation grid electrode 11 and cathode 12. Anode 14 is connected to one side of primary 24 of transformer 18. The anode direct current potential from terminal 23 is applied to anode 14 through a shunt resistance 27. A positive screen grid is connected to positive terminal 16 and lies between regulation grid 11 and control grid 13. A resistance 28 is connected between anode 14 and grid 21 and is adjusted to balance the size of the compensation current. The compensation action occurs by the currents from grid 21 and anode 14 merging and balancing out before being applied to the transformer, to neutralize shock impulses due to potentials applied to grid 11. These currents could also be combined, using a split primary winding of the transformer as will be evident to those skilled in the art.

In systems where the signal frequency is at intermediate or radio frequency, means are provided to unite the compensation current with the modulation current, preferably at a position before the demodulator in such a way that the portion of the modulation current due to the action of the regulator potential is compensated therein.

In Figure 6 is illustrated a complete system in which the application is applied to dynamic range

control of a phonograph reproducing system. A sound disk 30 cooperates with a tone arm or pick-up 31 for producing electrical signal variations across potentiometer control 32, the terminals of which are connected to the input circuit of amplifier stage 33 between cathode 34 and control grid 35 thereof. The output of amplifier 33 is arranged in accordance with the principles of the invention already described to eliminate shock excitation from reaching the output of the coupling transformer 36. The primary 37 thereof is connected between anode 40 and grid electrode 41. The primary 37 is tapped for the application of the positive voltage from terminal 38. The position of the tap is determined for proper compensation and neutralization of shock impulses in a manner already described. Shield grid 42 is interposed between compensation grid 41 and anode 40 and receives its proper positive potential from a voltage divider formed by resistances 43 and 44 connected between positive terminal 38 and ground.

The regulation grid 45 is energized by rectified potentials derived from the audio frequency signals in the following manner: The audio signal generated by pick-up 31 is applied to grid 50 of triode 51 through lead 52 and coupling condenser 53. The output of triode 51 is connected to transformer 55 in a conventional manner. The circuits for triode amplifier 51 are also conventional as will be evident and need not be further described. The output of transformer 55 is connected to a full wave rectifier 56 in a conventional manner. The output of rectifier 56 is supplied from cathode 57 thereof and center tap 58 of the secondary of transformer 55. The rectified output of rectifier 56 is filtered by means of condenser 60 which is shunted by resistance 61. Resistance 61 is preferably a potentiometer having a variable tap 62 from which the relative value of the regulation potential is determined and applied directly to regulation grid 45 of tube 33.

A further filtering condenser 63 is connected across the output of potentiometer 61. The average direct current value of the regulation potential applied to control grid 45 is controlled by potentiometer 65 connected at the opposite terminal to ground potential. A manual level control may thus be effected by the use of potentiometer 65.

The amplification level of the signals applied to control grid 35 of amplifier stage 33 is varied in amplification in accordance with the regulation potential applied to grid 45 as will now be evident. A dynamic volume expansion system is thus provided as will be understood by those skilled in the art. The output of coupling transformer 36 is applied to a conventional audio frequency amplifier 70, to the output of which a reproducer 71 is connected such as a loud speaker unit. The advantage of the present system is the compensation and neutralization of direct current shocks or impulses which may be applied to regulation grid 45, in a manner hereinabove described.

A further feature of the invention resides in providing an undistorted automatic dynamic expansion or volume range control of a signal band. It is well known that dynamic regulation or so-called dynamic expansion is employed for widening the sound level in translation thereof. In a broadcast transmission, musical and other wide range sound renditions are contracted in their range from the original intensity range to that necessitated by the capacity of the transmitting

equipment. Similarly, sound record reproductions are also contracted in range and the signals derived therefrom may be advantageously dynamically expanded to more closely represent the original sound ranges.

In conventional dynamic expanders, a single control or regulation potential is derived by filtering the rectified signal current and applied to a regulation electrode in an amplifier stage of the system. Inasmuch as good filtering is desirable for undistorted action, increased filtering adds to the inertia or sluggishness of the regulation control. It has not been practical in single control systems to sufficiently filter the control potentials to a point which is necessary to avoid all distortions due to residues of audio frequency rectification. In practice, the frequencies lying in the band from thirty to about two hundred cycles per second are appreciably distorted as a result of the dynamic regulation using the full band and efficient filtering. Such distortion might be obviated by suppressing frequencies of this band before passing onto the control or filtering circuit. However, this action would impair the dynamic expansion action since it would then be dependent only upon the volume due to the frequencies above that band.

The feature of the invention designed to overcome this deficiency lies in supplying a plurality of regulation potentials acting in the same direction upon the regulator circuit. Thus, for example, one of the potentials is derived solely from the low frequency band, for example, thirty to two hundred cycles, and a second regulation voltage from the rectification of frequencies above two hundred cycles. These independent regulation voltages are simultaneously applied to the regulation electrodes. Independent filtering of these components is thus made possible. The lower frequency bands are filtered by filters having relatively higher time constants than those of the higher bands. The practical result is that the regulation potentials, in combination, are substantially free from any traces of residue audio frequencies and cooperate to provide undistorted dynamic expansion. In this way, high fidelity low or bass note reception is assured in conjunction with the dynamic expansion action.

Referring to Figure 7 which is an embodiment of this feature of the invention a disk record 80 is indicated with a pick-up unit 81 generating the sound signals which are applied to the input of the tube 82 between control grid 83 and ground, which communicates to the indirectly heated cathode 84. The cathode is suitably biased through the self-biasing filter circuit 85-86. The signals are introduced to the tube through the level control potentiometer 87. A positive screen grid 88 is located beyond the control electrode 83 and is connected to a suitable point in the voltage divider 90-91 terminating in the source of positive supply 92. The output circuit of tube 82 originates between anode 93 and the cathode or ground, which includes the primary 94 of the output transformer 95. The output of transformer 95 is connected to audio frequency amplifier 96, in turn connected to reproducer unit 97 which is the loudspeaker.

The novel dynamic control circuit in accordance with the invention is connected to the output of the triode amplifier 100, the control grid 101 of which is coupled to the output of pick-up 81 through coupling condenser 102. The output of triode stage 100 is connected to the primary 103 of transformer 104. The transformer 104 has

two secondary windings 105 and 106, both of which naturally are impressed with the signal voltage but are electrically distinct. The secondaries 105 and 106 supply the independent channels for the rectification-filter-regulation circuit. The low frequency path in conjunction with winding 105 is designated, L; the high frequency path with winding 106, H.

The secondary 105 is shunted by a by-pass condenser 110. An impedance element 111 is connected between condenser 110 and winding 105. The values of impedance 110-111 are proportioned to by-pass the audio-frequencies, for example above 200 cycles per second. Accordingly, all audio frequencies below 200 cycles per second are introduced to thermionic rectifier unit 112. The unidirectional output of rectifier 112 is filtered by shunt condenser 113 and resistance 114. The adjustable output of the filtered signals is controlled by tap 115 on potentiometer 114. A further by-pass condenser 116 is shunted across the output of potentiometer 114.

In a similar manner a filter is provided across the output of winding 106 to by-pass the frequencies below 200 cycles in this case. The high pass filter is shown comprising resistance elements 120 shunted across the secondary, and a series condenser 121. It is to be understood that filter 120-121 is merely shown for schematic purposes and in practice, may comprise different arrangements and different types of impedance elements, such as impedances in place of resistances. Filter 120-121 is designed to pass frequencies above 200 cycles in the present case, for example, 200 to 10,000 cycles. This high frequency band is rectified by series rectifier unit 125, the output of which is shunted by a filter composed of condenser 126 and potentiometer 127. The variable tap 128 of potentiometer 127 is used to adjust the value of the signal voltage from the high frequency path. A by-pass condenser 129 is connected across the output of potentiometer 127.

In accordance with the present invention the filter 113-114 at the output of the low pass control section L is designed with a substantially higher than normal time constant. The higher time constant naturally provides a greater filtering action by the filter, as is well known in the art. The improved filtering action of the band between 30 and 200 cycles per second prevents harmonics and components thereof from passing on to the regulator electrode.

The filter 126-127 of the high frequency section H is of the order of the ordinary filters for dynamic regulators with the time constant small enough so that the control action responsive thereto will properly operate the dynamic expansion. The frequencies above 150 or 200 cycles are properly filtered by 126-127. In a preferred example the filter 113-114 is arranged with a discharge time constant of 1 second, condenser 113 being 2 microfarads and resistance 114 being 0.5 megohm. The discharge time constant of filter 126-127 of section H may be arranged for a discharge time constant of the order of 200 milliseconds.

The output from the respective filters is connected in series and forms a unitary direct current potential control for the regulation electrode 130. As shown in Figure 7 the respective outputs of potentiometers 114 and 127 are connected in additive series relationship across the variable tap portions 115 and 128 thereof, the negative terminal of the potentiometer being connected to ground by lead; and the resultant positive side

thereof being connected to electrode 130 through by lead 132.

It is to be understood that the invention is applicable with more than two rectified contiguous bands of the audio frequency spectrum used. A suitable band selection may be 30 to 200 cycles for the low; 200 to 2,000 for the intermediate and 2,000 to 10,000 for the high band.

It is to be understood that the described principle of undistorted dynamic volume expansion may be applied equally well to radio frequency or intermediate portions of radio receiver. However, it is preferable to use it particularly in the audio frequency section in the manner described since it is available for phonograph reproduction as well as radio reception.

According to a further modification, the invention may be applied to amplifying systems for automatic fidelity control such as for needle scratch suppression in phonographic pick-up systems.

An arrangement of this type is shown in Figure 8 comprising a multi-electrode tube having an indirectly heated cathode 133 followed in the order named by a first (signal) control grid 134, a screen grid 135 maintained in a known manner at a steady positive potential with respect to the cathode, a positive or anode grid 136, a further (regulation) control grid 137 and an anode or plate 138. The audio frequency signals impressed upon the grid 134 from a pick-up device or the like are amplified and applied from both the anode grid 136 and the anode 138 to the primary of the output transformer 141 feeding a subsequent amplifier indicated by the rectangle 142 before being impressed upon a translating device such as a loud speaker 143. The output paths from the grid 136 and plate 138 are designed to have different frequency characteristics and to this end the anode grid 136 in the example shown is directly connected to the upper end of the transformer primary 141 while the anode 138 is connected to the same end of the transformer winding through a high frequency stop or noise suppression filter comprising a series induction coil 139 having its opposite ends bypassed to the cathode through condensers 140. The control potential is obtained by rectifying a portion of the sound output energy by means of rectifier 144 and filtering of the rectified energy by condenser 145 in such a manner as to obtain a control voltage developed across resistor 150 varying in accordance with the average intensity of the sound signals being amplified. This control voltage serves to negatively bias the regulation grid 137 in series with an additional fixed negative biasing source 151.

The operation of this circuit will then be as follows: If the intensity of the sounds increases, the bias on the grid 137 will become more negative with the result that the anode output path including the noise filter 139, 140 will be more or less blocked thereby opening the output path from the grid 136. On the other hand, if the sound intensity decreases more output signals will pass through the anode circuit thereby increasing the effectiveness of the noise filter.

Figure 8 includes the following further conventional elements; a record disk 148 cooperating with a tone arm or pick-up 146 connected to the input grid 134 by way of an audio frequency transformer 147. As is seen in the system as described, the effectiveness of the needle scratch or noise filter will be automatically controlled in dependence upon the average sound

intensity in such a manner as to maintain the most favorable compromise between optimum fidelity and noiseless reception under varying sound intensity conditions.

Referring to Figure 9, there is shown an automatic thermionic regulator tube for obtaining both dynamic range or volume control as well as automatic selectivity adjustment, i. e. in other words, combining the advantages of Figures 7 and 8. The tube employed in the example illustrated comprises the following electrodes in the order named: a cathode 155, a first control grid 156 serving for producing dynamic range control, a first anode or output grid 157, a screen grid 158 maintained in a known manner at a steady positive potential with respect to the cathode, a signal input grid 159, a further output or anode grid 160, a further control grid 161 serving for producing automatic fidelity or noise control and a plate or anode 162. A needle scratch filter comprising series inductance 163 and by-pass condensers 164 is connected between the plate 162 and a first primary winding 166 of the output transformer 165. Anode grid 160 is directly connected to the transformer 166 to obtain fidelity or noise control in the manner substantially similar to Figure 8. The transformer 164 has an additional primary winding 167 and a secondary 168 connected to amplifier 169 which in turn serves to energize a further output transformer 170 having three secondary windings 172, 173, 174, one of which (172) energizes loud speaker 171. Windings 173, 174 serve to derive portions of the audio signal energy rectified by means of rectifiers 175 and 176 followed by smoothing filters 177 and 178 to produce control potentials varying in proportion to the average sound intensity. One of these control potentials is impressed upon the dynamic range control grid 158 and the other control potential is impressed upon fidelity control grid 161. The grids 156 and 161 are additionally negatively biased by steady biasing sources 179' and 179" in a manner substantially similar to that shown in Figure 8. The output from the positive or anode grid 157 is passed through the primary coil 167 of the transformer 165 arranged in such a manner as to compensate direct current impulses in the primary coil 166 due to sudden potential variations on the control grid 156. To this end the coils 166 and 167 are suitably designed and wound in a proper sense to effect complete neutralization of D. C. shocks or impulses. Item 152 is a record disk 153, a tone arm or pick-up and 154 the input transformer for impressing the audio signals upon grid 159 and cathode 155 in series with a suitable fixed negative biasing source 179. It is seen, therefore, that an arrangement according to Figure 9 will enable by the aid of a single tube simultaneous dynamic range (compression or expansion) and fidelity (noise or needle scratch) control while at the same time substantially eliminating the disturbing effects of D. C. shocks or impulses due to sudden or abrupt changes in control potential.

As is understood, in Figures 8 and 9 the anode 138 or 162 may be directly connected to the output transformer and the scratch filter may be inserted in the path from the anode grid 136 or 160, respectively, in which case however the control potential on the grid 137 and 161, respectively, should be reversed to secure the same function and results as pointed out.

It will further be evident that arrangements

according to Figures 8 and 9 are not limited to the amplification of audio signals but will apply with equal advantage to radio frequency amplifiers.

From the foregoing it will be understood that the invention is applicable to various modifications which will suggest themselves to those skilled in the art and accordingly the specification and drawings presented herein are to be regarded in an illustrative rather than in a limiting sense short of the scope of the invention as defined in the appended claims.

What is claimed is:

1. In combination with an electron discharge device comprising a cathode and an anode, a signal control grid near the anode, an amplification control grid near the cathode and a compensation grid interposed between said signal and amplification control grids, an input circuit connected between the cathode and signal control grid, output impedance means connected between the anode and said compensation grid, a source of space current for said discharge device connected between the cathode and an intermediate point of said impedance means, an amplification control circuit connected between said amplification control grid and said cathode, a screen grid at cathode signal potential interposed between said compensation and signal control grids, said intermediate point being so chosen that current through said impedance means due to potential on said amplification control grid is compensated.
2. In combination with an electron discharge device comprising a cathode and an anode, a signal control grid near the anode, an amplification control grid near the cathode and a compensation grid interposed between said signal and amplification control grids, an input circuit connected between the cathode and said signal control grid, output impedance means connected between said anode and said compensation grid, a source of space current for said discharge device connected between the cathode and an intermediate point of said impedance means, an amplification control circuit connected between said amplification control grid and said cathode, a screen grid at cathode signal potential interposed between said amplification control and compensation grids.
3. In an automatically controlled amplifier for electric signals, an electron discharge device comprising a cathode, an anode, a signal control grid near said anode, a regulation grid for controlling the amplification near said cathode and a compensation grid between said signal control and regulation grids, an input circuit connected to said signal control grid and said cathode, output impedance means connected between said anode and said compensation grid, a source of space current for said discharge device connected between the cathode and an intermediate point of said impedance means, means for averaging a portion of the signal energy being amplified to derive a direct control potential varying in proportion to the average signal amplitude, means for applying said control potential to said regulation grid, a screen grid at cathode signal potential interposed between said signal control grid and said compensation grid, the intermediate point of said impedance means being chosen so that current through said impedance means due to potential on said regulation grid is compensated.
4. In combination with an electron discharge

tube comprising a cathode and an anode, a signal control grid near said anode, an amplification control grid near said cathode and an anode grid interposed between said signal and amplification control grids, an input circuit connected to said signal control grid and said cathode, output impedance means connected between said anode and said anode grid, a source of space current for said tube connected to an intermediate point of said impedance means and said cathode, an amplification control circuit connected to said amplification control grid and said cathode, a screen grid at cathode signal potential interposed between said anode grid and said signal control grid, and means for balancing the currents developed in the branches of said impedance means at opposite sides of said intermediate point due to varying potential on said amplification control grid.

5. In combination with an electron discharge tube comprising a cathode and an anode, a signal control grid near said anode, an amplification control grid near said cathode and an anode grid interposed between said signal and amplification control grids, an input circuit connected to said signal control grid and cathode, output impedance means connected between said anode and said anode grid, a source of space current for said tube connected to an intermediate point of said impedance means and said cathode, an amplification control circuit connected to said amplification control grid and said cathode, a screen grid at cathode potential located between said amplification control grid and said anode grid, and means for substantially balancing the currents developed in the branches of said impedance means at opposite sides from said intermediate point due to varying potential on said amplification control grid.

6. In an amplifier including an electron discharge tube provided with a cathode, a main anode, a compensation anode, a signal control grid and an amplification control grid, an input circuit connected between said signal control grid and said cathode, a common output circuit for said main and compensation anodes, means for applying control potential to said amplification control, further means including circuit connections from said main and compensation anodes to said output circuit for balancing the output currents due to potential variations on said amplification control grid, and means for substantially preventing said signal control grid from affecting the current to said compensation anode.

7. In an amplifier including an electron discharge tube provided with a cathode, a main

anode, a signal input grid near said anode, an amplification control grid near said cathode and a foraminous auxiliary anode located between said signal and amplification control grids, an

5 input circuit connected between said signal control grid and cathode, means for applying control potential to said amplification control grid, a common output circuit for said main and auxiliary anodes, means including circuit connections from said anodes to said output circuit to balance the output currents due to potential variations on said amplification control grid, and means for substantially preventing said signal control grid from affecting the current to said auxiliary anode.

10 8. In an amplifier including an electron discharge tube provided with a cathode, a main anode, a signal input grid near said anode, an amplification control grid near said cathode and a foraminous auxiliary anode located between said signal and amplification control grids, an input circuit connected between said signal control grid and said cathode, means for applying control potential to said amplification control grid, a common output circuit for said main and auxiliary anodes, means including circuit connections from said anodes to said output circuit to balance the output currents due to potential variations on said amplification control grid, and means for substantially preventing said signal control grid and said auxiliary anode.

15 9. In an amplifier including an electron discharge tube provided with a cathode, a main anode, a signal input grid near said anode, an amplification control grid near said cathode and a foraminous auxiliary anode located between said signal control and amplification control grids, an input circuit connected between said

20 40 signal control grid and said cathode, means including rectifying and filter means for averaging a portion of the signal energy being amplified to derive a direct current control potential varying in proportion to the average signal strength,

25 45 50 means for applying said control potential to said amplification control grid, a common output circuit for said main and auxiliary anodes, means including circuit connections from said anodes to said output circuit to balance the output currents due to potential variations on said amplification control grid, and a positively biased screen grid at cathode signal potential arranged between said signal control grid and said auxiliary anode.
